DESIGN FOR A COMBINATION COFFEE
TABLE AND BAR

Gordon Douglas, Los Angeles, Calif.

Application June 29, 1946, Serial No. 131,159

Term of patent 7 years

(Cl. D33—14)

To all whom it may concern:

Be it known that I, Gordon Douglas, a citizen of the United States, residing at Los Angeles, in the county of Los Angeles and State of California, have invented a new, original, and ornamental Design for a Combination Coffee Table and Bar, of which the following is a specification, reference being had to the accompanying drawing, forming part thereof.

In the drawing:

Fig. 1 is a front perspective view of a combination coffee table and bar, showing my new design; and

Fig. 2 is a rear perspective view of the article of furniture.

I claim:

The ornamental design for a combination coffee table and bar, as shown.

GORDON DOUGLAS.
